UNITED STATES PATENT OFFICE.

ALBERT H. NIRDLINGER, OF ROCHESTER, NEW YORK.

DESIGN FOR A NAME-PLATE FRAME FOR BURIAL-CASKETS.

SPECIFICATION forming part of Design No. 12,443, dated August 30, 1881.

Application filed June 15, 1881. Term of patent 7 years.

To all whom it may concern:

Be it known that I, ALBERT H. NIRDLINGER, of Rochester, Monroe county, New York, have invented and produced a new and original Design for Name-Plate Frames for Burial-Caskets; and I do hereby declare that the following is a full, clear, and exact description of the same, reference being had to the accompanying drawings, in which—

10 Figure 1 is a perspective view, and Fig. 2 a cross-section, of the device.

My new design relates to name-plate frames for burial-caskets, which frame contains the name-plate and rests upon the central cross-15 panel of the casket.

In the drawings, A represents the base-piece upon which the name-plate rests. At the outer edge is a convex molding, a, and above this is a second convex molding, b, which is placed 20 inside the first, so that the two moldings present successive steps. In plan view the moldings are of rectangular form. Inside the upper molding is a cavity or socket, c, in the bottom of which the name-plate is placed. The 25 inner sides of the molding b form a bevel, d, which slants inward toward the center. On

top of the four corners of the upper molding are ornamental studs or buttons *etc.* The outer edges of the two moldings being narrowing toward the top and presenting two convex outlines, and the upper one being beveled on the inner side, the appearance is graceful and ornamental.

What I claim as new is—

1. The design for a name-plate frame, consisting of the two convex moldings *a b* at the outer edge of the base-piece, with a cavity, *c*, in the center, as herein shown and described. 35

2. The design for a name-plate frame, consisting of the two convex moldings *a b* at the outer edge of the base-piece, with a cavity, *c*, in the center, and a bevel, *d*, extending inward from the top of the upper molding to the bottom of the cavity, as herein shown and described. 40

In witness whereof I have hereunto signed my name in the presence of two subscribing witnesses.

ALBERT H. NIRDLINGER.

Witnesses:
